UNITED STATES PATENT OFFICE.

SAMUEL J. BAIRD, OF COVINGTON, KENTUCKY.

BUTTON-HOLE ATTACHMENT FOR SEWING-MACHINES.

SPECIFICATION forming part of Letters Patent No. 242,248, dated May 31, 1881.

Application filed August 12, 1880. (Model.)

To all whom it may concern:

Be it known that I, SAMUEL J. BAIRD, of the city of Covington and State of Kentucky, have invented certain Improvements in Button-Holing Attachments for Sewing-Machines, of which the following is a specification.

My invention relates to that class of button-hole attachments which consist of a cloth-clamp provided with devices for imparting to it a feed motion carrying the button-hole longitudinally under the needle, and for causing at the same time an oscillation for forming the stitch, the needle alternately entering the slit of the button-hole, or the line on which it is to be cut, and the cloth back of it.

In the drawings, Figures 1, 2, and 4 are respectively a plan, side, and end view of the device. The other figures represent detached portions of it.

20 In Figs. 1 and 2 the cloth-clamp appears in position. It consists of two strips of plate-steel, A and B, spring-tempered, and riveted or screwed together at one end, *a*. The other end is formed into jaws for holding the cloth which is to be introduced between them.

25 In clamping the cloth it is essential that the pressure be adapted to the thickness of the fabric and maintained until the operation is finished. Heretofore this has been arrived at 30 by means of adaptations of the well-known clamping-eccentric and clamping-screws with suitable accessories and other devices which need not be specified.

35 In the present device the elongated extremities of the clamp-pieces are so bent that in bringing them together the points or forward extremities of the clamp come together first, and the parallelism and continuous pressure of the two jaws are effected by the straightening 40 of the bent elongated spring-pieces of the clamp, which is effected as follows: About midway between the ends of these pieces a loop or staple, C, is made fast to the lower piece and incloses the upper, between which 45 and the staple a sliding wedge, D, is inserted, the adjustments of which are effected by means of a perpendicular flange or thumb-piece at one end. By the sliding of this wedge such pressure is brought to bear upon the clamp-pieces as causes them to straighten out, so as 50 to thus readily bring the jaws into a parallel adjustment to any thickness of fabric.

It will be observed that the upper side of the longitudinal wedge is a gradual incline, which, at its lower extremity, is terminated by 55 an abrupt descent to the horizontal extension of the piece, which, resting on the clamp-piece, ends in a perpendicular thumb-piece. This conformation of the wedge is requisite to give convenient effect to the spring action of the 60 clamp-pieces. The incline of the wedge is limited in its office to the adjustments requisite for different thicknesses of goods. It therefore requires to be but slight and short, while the abrupt descent at its end serves to release 65 the clamp-pieces instantaneously and altogether from the pressure of the wedge, and leaves the jaws free to separate for receiving the fabric. A rack cut in the edge of the lower clamp-piece engages with the pinion E on the 70 ratchet-wheel F, Figs. 3 and 7. These, revolving, by means which will be described presently, first in one direction and then in the other, impart to the clamp and to the cloth which it carries a reciprocal longitudinal motion. 75

A bridge, G, Figs. 1 and 4, spans the device and holds its parts together, being fastened to the bottom plate by screws or rivets *n n'* at its ends. From the bridge, near its center, a flange or post, I, rises perpendicularly, in the upper 80 end of which is the pivot-screw *e*, upon which the driving-lever P, Fig. 2, is fulcrumed. Through this lever all the movements of the attachment are derived from the sewing-machine. Its long arm *o* extends in a horizontal 85 direction, its end being connected with the needle-bar of the machine by a loop to be slipped over the head of the needle-screw, or by other suitable means. The lever is thus caused to oscillate perpendicularly in harmony 90 with the reciprocation of the needle-bar. The short arm *p* is bent downward to the bottom plate of the attachment, so that the perpendicular oscillating motion of the long arm is converted into horizontal motion at the end of 95 the short one. This end enters a hole, *b*, cut in the pawl-carrier L, Fig. 3, thus causing the carrier to slide back and forth with the motion of the lever. The carrier is a metal plate, which, by means of flanges, guide-pins, or equivalent devices, is so guided upon the bottom plate, on which it rests, that when driven by the lever it moves accurately in the direction of the length of the attachment. It is fur- 100

nished with two pawls, T and U, by the agency of which all the ultimate movements of the device are accomplished.

The pawl T is a transverse piece of plate-
5 metal, at the ends of which two parallel arms project in the direction of the ratchet-wheel F, Fig. 3. This piece is held in position by pins, lugs, or flanges on the carrier-plate e e', Fig. 3. The pawl is thus carried with the plate in its
10 longitudinal movement, but is susceptible of limited lateral adjustments on the carrier. The arms at the ends of the pawl-piece are at such a distance apart that when it approaches the ratchet-wheel, if adjusted on the center of the
15 carrier-plate, neither arm will engage with the ratchet; but if set over a little to the right or left one arm engages it, while the other is set off proportionally from it. The ratchet and pinion are thus caused to revolve in the one or
20 other direction, or to remain stationary, according to the adjustment of the pawl. The changes in the position of the pawl T, by which the movements of the ratchet-wheel are thus governed, are effected by means of a guide-
25 slot, m, in the plate K, Figs. 3 and 5. This plate is secured to the under side of the bottom plate, H, by means of a pivot-screw, i, Fig. 5. Moving on this pivot, the plate is sus-
ceptible of a limited lateral adjustment, which
30 is made by the operator by means of the handle J, by a lever, cam, and crank, or other equivalent appliance. The slot m is by this means brought to the center of the line of move-
ment, or to the one side or the other, at the
35 pleasure of the operator.

The pin f, Fig. 3, in the double pawl passes down through an opening in the bottom plate and enters the guide-slot m, which it traverses in its reciprocating movement. The lateral
40 adjustment of the plate K with the guide-slot m causes a coincident lateral movement of the pin f, carrying with it the double pawl, which is thus brought into each of the positions in relation to the ratchet-wheel, as required. The
45 forward end of the guide-slot is widened, so as to allow free lateral movement to the pawl as it engages and carries forward a tooth of the ratchet in the curve which it describes, and to admit of the retreat of the pawl without drag-
50 ging the ratchet, while the return of the pin f into the narrower part of the slot restores the pawl into position to engage the next tooth.

A pin in the bottom piece and three holes at l, Figs. 3 and 5, in the wing of the adjust-
55 ment-plate, into which it may drop, or equivalent devices, may be used to mark the positions of adjustment.

While the feed movements are effected and governed by these devices the lateral oscillation of the cloth-clamp is coincidently accom-
60 plished by the following means: Fig. 5 repre-
sents the adjustment-plate K, together with a second ratchet-wheel, M, and a cam-wheel, N, which are so fastened as to revolve together,
65 and are pivoted on the plate by a screw or post at q. The ratchet M has ten teeth and the cam-
wheel five equal and equidistant knobs or cams

on its periphery. These coincide with alter-
nate teeth on the ratchet. To the latter inter-
rupted circular motion is given by means of a
70 second pawl, U, Figs. 5 and 6, the latter of
which is a perspective view. This is a trans-
verse plate, held in position on the pawl-car-
rier in a manner similar to that of the pawl
T, already described, so that it is in like man-
ner susceptible of limited lateral adjustment,
75 which, however, takes place automatically. At
or near the end of this piece is a flange or pro-
jection, x, bent downward at a right angle, so
as to pass through slots s in the intervening
80 pieces and engage with the ratchet-wheel M.
Across the middle of the pawl-piece is cut a
slot, u, through which the point of the pivot-
pin q of the ratchet M projects. Toward the
forward end of the slot, on the side opposite to
85 the pawl-flange, there is an inward incline, by
which the slot is narrowed in the direction of
the front. The slot is cut at such a distance
from the pawl-flange that in the forward move-
ment of the carrier, the pawl being laterally ad-
90 justed by the sides of the slot engaging on the
pivot-pin, the flange is brought in contact with
a tooth of the ratchet, which it carries forward,
the pawl shifting laterally by a sliding move-
ment to correspond with the curve described
95 by the tooth. In this movement the wide end
of the slot allows the adjustment in relation to
the pivot-pin q; but upon the retreat of the
pawl the incline comes in contact with this pin,
which causes the pawl to slide laterally back
100 into position to take hold of the next tooth of
the ratchet upon the next advance of the car-
rier. One tooth of the ratchet is thus moved
forward at each reciprocation of the pawl, and
with it the cam-wheel is so rotated as to pre-
105 sent on a given side alternately a projecting
cam and a blank or plain segment of the wheel.

The clamp-piece A, Figs. 1, 2, and 7, in its longitudinal movement, slides on the clamp-
slide O, side flanges on which, rr, fit to its par-
allel sides. Two flanges or posts, t t, Figs. 4
and 5, on the tail of the clamp-slide descend
110 through the bottom plate and embrace the cam-
wheel between them. The distance between
these posts is equal to the greatest diameter of
the cam-wheel. The result of the revolution
115 of the latter is that the cams engage the posts
alternately on the one side and the other, thus
causing an oscillation of the clamp-slide, which
is pivoted on the axis of the ratchet and pin-
ion F E, Figs. 1 and 7. Through the flanges
120 rr this oscillation is transmitted from the
clamp-slide to the clamp, with the feed motion
of which it coincides.

The adjustment of the pawl U and operation
125 of the device here described will be equally ac-
complished whether the slot u is in the pawl
and the pin or post q in the adjustment-plate
or the reverse.

The pivot on which the ratchet and cam
wheels M and N revolve being a post or screw,
q, in the adjustment-plate K, it is laterally
shifted, and the wheels with it, by the move-
ments of that plate, as already described, for

engaging the double pawl alternately with the opposite sides of its ratchet F. This consequent alternate engagement of the arms of the double pawl with the ratchet F operates to produce two sets of oscillations adjacent and parallel, one in the forward movement of the clamp and the other on its return. The two sides of the button-hole are thus in succession presented to the needle, and thereby formed, and the adjustment of the plate on the middle releases the ratchet from the action of the double pawl, as already explained, and thus suspends the feed movement, while the oscillation, continuing on the line intermediate between the two sides of the button-hole, plants a few stitches across the end.

The combination of ratchet-wheel, double pawl, and adjustment-plate for arresting and reversing the circular movement of the ratchet F, as herein described, is as applicable to a scroll or cam movement as to the rack and pinion here specified.

The mode of operation of the different parts of the device has been shown sufficiently in the details already given in the foregoing specification.

What I claim as new and of my invention is—

1. In combination, the elongated spring cloth-clamp, staple C, and the wedge having a thumb-piece and a gradual incline, terminating in an abrupt descent to that portion of the wedge which rests on the clamp-plate, substantially as and for the purposes specified.

2. In combination, the elongated spring 35 cloth-clamp, staple C, and the wedge whose upper side consists of a gradual incline, terminating in an abrupt descent to the horizontal extension of the piece, which, resting on the clamp-plate, ends in a perpendicular thumb- 40 piece, substantially as and for the purposes specified.

3. A springless double pawl, T, laterally adjustable, with a pin traversing the slot m in a guide-piece, in combination with a ratchet- 45 wheel, F, and clamp-slide, substantially as and for the purposes specified.

4. A slide-pawl, U, adjustable to the ratchet M by a slot and pin, in combination with the ratchet and cam wheels and clamp-slide, sub- 50 substantially as and for the purposes specified.

5. The ratchet and cam wheels M and N, in combination with the adjustment-plate, substantially as and for the purposes specified.

6. The ratchet and cam wheels M and N, in 55 combination with flanges or posts on the clamp-slide, substantially as and for the purposes specified.

7. The combination of the ratchet and cam wheels, the clamp-slide provided with flanges 60 or posts t t, the plate K, provided with a pin, q, and slide-pawl U, provided with the slot u, substantially as and for the purposes specified.

SAMUEL J. BAIRD.
